UNITED STATES PATENT OFFICE.

CHESTER D. MILLER, OF SAN DIEGO, CALIFORNIA.

INTERNAL-COMBUSTION ENGINE.

1,065,461.

Specification of Letters Patent. Patented June 24, 1913.

Application filed July 31, 1912. Serial No. 712,489.

To all whom it may concern:

Be it known that I, CHESTER D. MILLER, a citizen of the United States of America, residing at San Diego, in the county of San Diego and State of California, have invented certain new and useful Improvements in Internal-Combustion Engines, of which the following is a specification.

This invention relates to internal combustion engines, and more particularly to an improved valve structure for such engines.

The object of the invention is to provide a rotary valve adapted to serve both as an inlet and an exhaust valve, together with improved means for cooling and lubricating such valve. This valve may be employed in conjunction with either single or multiple cylinder engines.

Further objects and advantages of the invention will be set forth in the detailed description which now follows.

In the accompanying drawing, Figure 1 is a side elevation of a gasolene engine constructed in accordance with the invention, and Fig. 2 is a transverse vertical section therethrough.

Referring to the drawing, the numeral 5 designates the cylinders, 6 the pistons and 7 the connecting rods of the engine. The cylinders (see Fig. 2) are provided with water jackets 8 of the usual and well known type. A valve casing 9 is secured in position upon the cylinders by means of cap screws 10. This valve casing comprises an outer wall 11 and inner wall 12, of a water jacket 13. In addition, this valve casing comprises a core consisting of walls 14, 15, 16 and 17. A passage 18 is formed through the core between the walls 14 and 15, and it will be seen that the wall 14 forms one side of the core. The wall 17 forms the opposite side of the core, and between this wall 17 and wall 16, a water jacket 19 is provided. An exhaust channel 20 is formed longitudinally through the core and communicates with an exhaust pipe 21. A water pipe 22 leads into the water jacket 19 at the end thereof.

The valve proper is indicated at 23, and this valve has diametrically opposed ports 24 formed therein, there being two of these ports for each cylinder. Arranged opposite the outlet 25 of the inlet port 18 is an inlet port 26 leading into the engine cylinder, and arranged opposite a port 27, which communicates with exhaust channel 20 is exhaust port 28 leading from the cylinder.

The spark plug is indicated at 29.

30 indicates longitudinally extending friction blocks to which oil may be conducted by pipes 31. These friction blocks 30 lubricate 69 valve 23 and also pack it to prevent escape of the gases.

32 is the fuel supply pipe.

Rotation is imparted to the valve by means of a worm wheel 33. Motion is imparted to this worm wheel by a worm 34 mounted upon a shaft 35 that is journaled in bearings 36. At its lower end this shaft carries a second worm 37 which meshes with a worm wheel 38 upon the main shaft 39 of 70 the engine.

Surrounding valve 23 between two of the cylinders are two expanding compression rings 40.

41 is water space.

Friction blocks 30 have coiled springs 42 to force them against the valve cylinder.

43 are oil grooves.

The operation of the device is as follows: When the ports 24 lie in alinement with pipe 32 and port 26, it is apparent that they will also lie in alinement with the entrance to and the outlet from port 18 whereupon through it, fuel may pass through port 26 into the engine cylinder. When ports 24 85 come into alinement with port 28, it is apparent that communication will be established between the cylinder and the exhaust channel 20. Since there are two ports 24, and since these ports are diametrically opposite each other, it follows that a single rotation of the valve will take place during eight complete strokes of the engine. It is for this reason that a worm gearing is provided for driving the valve. This structure 95 renders it possible to utilize a valve of this type which will travel at a comparatively slow rate of speed, thereby avoiding overheating, and consequently avoiding in large measure, the evil effects arising from excessive deposits of carbon occasioned by the extreme heating of the lubricating oil. The friction blocks 30 efficiently lubricate the valve and prevent the escape of the gases under pressure past them.

I am aware of the fact that it has been proposed to use rotary valves, but I am not aware that a rotary valve comprising merely a cylindrical shell operating about a fixed core and within a water jacket, said core being constructed as herein set forth, has ever been employed. The central part of my core

serves as an exhaust channel. This core, at the side through which the hot exhaust gases must pass, is efficiently cooled by the water jacket 19, while the opposite side of the core, 5 that is wall 14, is kept sufficiently cool by the passage of the gasoline vapor laden air passing through port 18. In addition to this, the incoming charge is forced to travel around the curved wall 15. Since this wall 10 is one of the walls of the exhaust channel, it follows that it will be comparatively hot and consequently the charge will be warmed as it is drawn into the cylinder. This renders it easy to ignite the charges and consequently 15 produces a more effective engine.

While the elements shown and described are well adapted to serve the purposes for which they are intended, it is to be understood that the invention is not limited to the 20 precise construction set forth, but includes within its purview, such changes as may be made within the scope of the appended claims.

Having described my invention, what I 25 claim is:—

1. In a valve structure for explosive engines, a valve casing comprising a core, a wall spaced from said core, a cylindrical valve rotatively mounted between said wall 30 and said core, there being an exhaust channel formed longitudinally through said core and there being an intake passage formed transversely through said core and a water jacket formed in said core upon the side 35 opposite the intake passage, said intake passage lying adjacent the opposite side wall of the core.

2. In a valve structure for explosive engines, the combination with a casing comprising an outer water jacket and an internal core, of a rotative cylindrical valve disposed between said water jacket and said core, said core having a longitudinally extending exhaust channel formed there- 40 through, and said core having a transversely extending inlet passage formed therethrough, one wall of which is formed by a wall of the exhaust channel, said core having a water jacket formed therewith 45 which lies upon one side of said core, said inlet passage lying upon the other side of said core.

3. In a valve structure for explosive engines, the combination with a casing comprising an outer water jacket and an internal core, of a rotative cylindrical valve disposed between said water jacket and said 50

core, said core having a longitudinally extending exhaust channel formed therethrough and said core having a transversely extending inlet passage formed therethrough, one wall of which is formed by a wall of the exhaust channel, said core having a water jacket formed therewith which lies upon one side of said core, said inlet passage lying upon the other side of said core, and said exhaust channel lying between said water jacket and said inlet passage. 60 65

4. In a device of the character described, the combination with a valve casing comprising an outer water jacket and an internal core spaced therefrom, of a cylindrical valve mounted for rotation therebetween, said cylindrical valve having diametrically opposed ports formed therethrough, an inlet passage extending transversely through said core and opening upon opposite sides thereof at diametrically opposed points, a centrally arranged exhaust channel formed longitudinally through said core, said core having a radially extending exhaust port leading from said channel to the periphery of said core, and a water jacket formed with said core and lying upon the side of said core through which said exhaust port passes. 70 75 80 85

5. In a device of the character described, the combination with a valve casing comprising an outer water jacket and an internal core spaced therefrom, of a cylindrical valve mounted for rotation therebetween, said cylindrical valve having diametrically opposed ports formed therethrough, an inlet passage extending transversely through said core, and opening upon opposite sides thereof at diametrically opposed points, a centrally arranged exhaust channel formed longitudinally through said core, said core having a radially extending exhaust port leading from said channel to the periphery of said core, a water jacket formed with said core and lying upon the side of said core through which said exhaust port passes, said inlet passage being formed between the wall of the exhaust channel and the external wall 90 95 100 105 of said core at the side of said core remote from said radially exhaust port.

In testimony whereof I affix my signature in presence of two witnesses.

CHESTER D. MILLER.
